(57)

CLAIM

The ornamental design for a ceiling fan motor housing, as shown and described.

DESCRIPTION

FIG. 1 is a top perspective view of a ceiling fan motor housing showing my new design;

FIG. 2 is a bottom perspective view thereof;

FIG. 3 is a top view thereof;

FIG. 4 is a bottom view thereof; and,

FIG. 5 is a front side view thereof, with rear, left and right side views being mirror images thereof.

The broken lines illustrate portions of the ceiling fan motor housing and form no part of the claimed design.
